Application March 2, 1937, Serial No. 128,568

23 Claims. (Cl. 197—133)

This invention relates to improvements in continuous billing machines and is directed toward an improvement in the machine described in application Serial No. 127,684, filed by Charles H. Beiderbecke, February 25, 1937.

The above application describes a continuous billing machine comprising the combination of a power operated typewriter with a liftable platen and a forms carrier adapted to handle a pack of continuous forms, whether fanfolded or in the form of superposed webs.

It is customary to actuate the feed rolls which cooperate with the platen to feed work sheets around the platen into engagement with the platen by means of fairly stiff springs in order to ensure that the work sheets to be typed upon will be firmly grasped by the platen and fed evenly.

In the billing machine described in the above application, when the platen is raised, the feed rollers are permitted to follow the movement of the platen for a short distance until stopped by suitable limiting means. When the platen is lowered to normal position, the spring which holds the feed rollers in contact with the platen offers a considerable resistance to downward movement of the platen with the result that it requires quite a little effort to firmly seat the platen in its home position and it sometimes happens that, owing to this opposing force offered by the feed roller operating spring or springs, the platen does not become firmly seated at both ends, if at all.

The present application is directed towards the provision of means for overcoming the above difficulty which, aside from the extra effort and other troubles incidental to overcoming of the force of the spring mentioned, there is sometimes a tendency for the forms to shift relative to each other due to uneven engagement with the feed rollers. This is due to the fact that the feed roller assembly is usually centrally pivotally supported and operated by a single spring to secure uniformity of pressure of the feed rollers upon the work sheet wrapped around the platen which pivotal mounting permits the feed roller assembly to tilt more or less to right or left when the platen is raised.

According to the present invention, means is provided to control the movement of the feed rollers whereby they are not permitted to engage the work sheets until the platen reaches its home position, yet, after the platen has finally reached its home position the feed rollers are left free to respond to their operating spring or springs

and press the work sheets firmly against the platen.

The single figure of drawings shows an elevation of the left-hand end of a carriage similar to the one described in the above application.

The platen 1 is rotatably mounted in arms, like 2, which are pivoted at 3 in plates 4 secured to the side plates 5 of the carriage. The side plates 5 are integrally joined by means of a channel-shaped member 6 which is secured to the plates 5 in any desirable manner, preferably by welding, brazing, or soldering. The member 6 has grooves formed therein which confront similar grooves in the usual carriage supporting rails 7 of the typewriter, which grooves serve as raceways for anti-friction roller assemblies 8 of well known form. The usual carriage release lever 9 pivoted at 10 is provided at each end of the platen and actuates a bail 11 which cooperates with a lug 12 formed in a lever the function of which is to release the usual escapement pawls to permit the carriage to be moved by hand to any desired position.

The arms 2 are integrally joined by means of a tube 13 through which passes a rod 14 to the ends of which are secured three-armed latch levers 15. Loosely pivoted on one end of the rod 14 is a platen lifting lever 16 having a pin 16a cooperating with one arm of one of the latch members 15. One arm of each latch lever 15 is formed with a hook-shaped portion 15a which engages a lug 17a formed in an adjustable plate 17 secured to plate 5, there being one such plate 17 at each end of the platen. Normally, the hook-shaped portions 15a engage the lugs 17a to hold the platen in lowered or writing position, springs 18 connected to the hook-shaped portions 15a and to pins carried by the arm 2 holding the latches in engagement with the lugs 17a, the platen is kept firmly seated in its normal position. However, there need be provided only one lever 16 which is preferably located at the left-hand end of the platen.

The numerals 19 and 20 designate the usual feed rollers which cooperate with the platen to feed the work sheets. These feed rollers are mounted upon shafts carried by a paper deflector frame 21 which supports the paper deflector 22. Pivotally mounted in the plates 5 in front of and below the platen 1 is a rod 23. Near the mid-point of this rod 23 there is secured an arm 24 having a bend near its mid-point in which rests a rod 24a extending parallel with the platen and forming part of the paper deflector and feed roller assembly. A plunger 25 is loosely

guided at its lower end by a hole in a bushing 25a screwed into a hole in the member 6 and at its upper end is socketed in a hole in the arm 24. A spring 26 loosely coiled around plunger 25 is 5 socketed by a shoulder in the upper end of plunger 25 and by the bushing 25a. Spring 26 presses the arm 24a upwardly whereby the feed rollers 19 and 20 are pressed firmly against the platen.

Normally, when the platen is raised, the spring 10 26, which must be fairly heavy to lift the paper deflector assembly with sufficient force to grip the work sheets firmly, will cause the paper deflector and feed roller assembly to follow the platen in its raising movement for a short distance and obviously this spring must be compressed in lowering the platen.

In order to relieve the operator of the additional work incidental to compressing the spring during the last part of the movement of the 20 platen to its home position mechanism is provided to cause this compression of the spring to take place gradually throughout a major portion of the downward movement of the platen; that is, to spread the work of moving the paper deflector and feed roller assembly downwardly over a longer period of time and accomplish it by levers whose mechanical advantage is one of force rather than speed.

Pivoted at 28 on the side of the arm 2 at the 30 left-hand end of the carriage is a double-armed latch lever 29 having one arm thereof engageable with the lug 17a and normally held in contact therewith by means of a spring 30 anchored to the other arm of lever 29 and to the same pin 35 which anchors the spring 18 to the arm 2. The three-armed latch lever 15 is provided with a latch arm 15b adapted to cooperate with a latching lug 29a formed in the lever 29. Normally, however, the lug 29a is clear of the end of latch 40 arm 15b. Pivoted at 31 to the arm 2 is a relatively long curved lever 32 connected by a spring 33 to a pin carried by the arm 2. The lever 32 has a pin 32a in the plane of one arm of the latch lever 15 whereby, when the latch member 15 is rocked counterclockwise, the lever 32 will be similarly 45 rocked by coaction of the pin 32a with the latch lever 15.

The lever 32 has a second pin 32b on the opposite side of the pivot 31 of the pin 32a. This 50 pin 32b is connected by a spring 33 to a pin carried by an arm 34 also pivoted at 31, the spring 32 normally holding the arm 34 in engagement with pin 32b. A pair of shroud plates 35 is riveted on opposite sides of the arm 34, which 55 plates serve as guides for the free end of a lever 36 which is secured to the rod 23. The arm 36 has a nose 36a opposite a similarly shaped nose 34a formed on the arm 34, and the latter is slightly thicker than the arm 36 whereby both the 60 arms 34 and 36 can move freely about their pivots.

When the platen is to be raised to permit the straightening of a pack of forms with interspersed carbon sheets for the purpose of shifting the carbon sheets, the lever 16 is grasped by 65 the operator's left hand and raised sufficiently to cause the pins 16a to operate the latch levers 15 at both ends of the carriage and disengage them from the lugs 17a. While the arm 16 is being raised in this fashion, the pin 32a is also pushed 70 upwardly by the lever 15, thereby rocking lever 32 counterclockwise. This causes the nose 34a to move to the right until it engages the nose 36a after a small amount of movement of the lever 32 and thereafter further movement of the arm 75 34 to the right is stopped until the platen has

been raised far enough for nose 34a to snap over nose 36a.

When the platen is fully elevated, the arms 2 are engaged by stop lugs 4a formed in the plates 4. The weight of the platen and the other parts carried by the arms 2 is counterbalanced by means of torsion springs 37 which are hooked around the edges of frames 4 and the edges of the arms 24, these springs also serving to hold the platen in elevated position. The spring 37 is not, 10 however, strong enough to raise the platen to the fully elevated position unaided, but merely serves to relieve the operator of most of the weight of the platen and other parts supported by the arm 2. 15

As the platen rises from the position shown in the drawing, the spring 30, holding the lower arm of lever 29 in engagement with lever 17a, gradually moves the upper arm 29a against the edge of the latching arm 15b whereby, when the hook portion 15a becomes fully disengaged from the lug 17a, the lug 29a engages the arm 15b and eventually snaps over said arm to hold the latching member 15 in the unlatched position. During the initial part of the movement of the platen to the elevated position, the feed rollers 19 and 20 follow the platen for a short distance as a consequence of the force imparted by spring 26 with the result that the nose 36a is moved upwardly, sliding along the edge of arm 34. However, as 30 the platen completes its movement, the arm 34 will be drawn upwardly, causing its nose 34a to travel in an arc and eventually the nose 34a will pass the nose 36a and will snap over the end of lever 36. With the platen in fully elevated position, the latch lever 29 will be holding the latch lever 15 in disengaged position while the lever 34 will have reengaged the pin 32b and the nose 34a now will occupy a position directly above the nose 36a in the end of lever 36. As the platen descends, 40 the nose 34a will press down upon the nose 36a and gradually force the arm 36 downwardly, thereby causing the feed rollers 19, 20 and paper deflector 22 to move downwardly as the platen descends, but considerably more slowly, owing to 45 the ratios between the levers. Eventually lug 17a will engage the lower arm of latch lever 29 and gradually disengage the lug 29a from the latch arm 15b. When the platen reaches its normal position, the hook-shaped portion 15a will snap 50 under the lug 17a and allow the arm 32 to become restored to its normal position, thereby permitting lever 32 to rock clockwise to free the nose 34a from the nose 36a and permitting the arm 36 to move upwardly a slight amount. Since 55 the nose 34a is slightly lower than the nose 36a, the lever 36 is always pushed downwardly slightly below its normal position from which it will be seen that the feed rollers do not actually exert pressure against the platen until it is in its home 60 position.

It will be noted that the radial distance from the center of rod 23 to the center of rod 24a is approximately one-fifth the radial distance from rod 23 to the nose 36a. Similarly, the radial 65 distance between the nose 34a and the center of pivot 3 for the arms 32 is very much smaller than the radial distance from the pivot 3 to the end of lever 16. It is clear, therefore, that the force which must be exerted by the operator to depress the paper deflector and feed rollers is so small as to be virtually negligible. Thus, instead of applying a relatively strong force practically directly to the platen during the last stages of its movement to home position to overcome the 75

- pressure of spring 25, the present invention provides a means whereby a negligible force is applied with a high leverage ratio throughout a major portion of the movement of the platen to 5 its home position. It will be seen, therefore, that practically no effort is required to raise or lower the platen since the weight of the platen and the parts carried by the arms is very nearly counterbalanced by the springs 31.
- 10 While there has been shown and described and pointed out the fundamental novel features of the invention as applied to a single embodiment it will be understood that various omissions and substitutions and changes in the form and de- 15 tails of the device illustrated and in its operation may be made by those skilled in the art without departing from the spirit of the invention. It is the intention, therefore, to be limited only as indicated by the scope of the following claims.
- 20 What is claimed is:
1. In a continuous billing machine, the combination of a displaceable platen, feed rollers cooperating with the platen to feed work sheets, means to press the feed rollers against the platen 25 and tending to cause the feed rollers to follow the platen in its displacing movement, and means to move the feed rollers back toward their normal position in advance of the restoration of the platen from a displaced position to its normal 30 position.
  2. In a continuous billing machine the combination of a platen movable from a writing position to release forms wrapped around the platen, feed rollers cooperating with the platen when in 35 its writing position to feed said forms, means to engage the feed rollers with the platen, said means tending to cause the feed rollers to follow the platen in its movement away from writing position; and means responsive to restoration of 40 the platen to writing position for moving the feed rollers back toward their normal position in advance of the platen.
  3. In a continuous billing machine, a platen; a carriage, means to movably mount the platen 45 in the carriage whereby the platen may be displaced from a writing to a non-writing position, feed rollers mounted on the carriage and cooperating with the platen when the latter is in writing position to feed work sheets, means urging the 50 feed rollers into engagement with the platen whereby the feed rollers follow movement of the platen to non-writing position when the platen is displaced, and means operated by the first-named means for moving the feed rollers back 55 toward their normal position in advance of the platen.
  4. In a continuous billing machine, the combination of a carriage, a platen, means to movably mount the platen in the carriage whereby the 60 platen may be moved from a writing to a non-writing position including an arm rockably mounted in the carriage, sheet gripping means cooperating with the platen when in its writing position for pressing work sheets against the platen, means to engage the sheet gripping means 65 with the platen whereby the sheet gripping means tends to follow the platen in its movements to the non-writing position, and means operated by said arm when the platen is restored for moving the sheet gripping means back toward their normal 70 position in advance of the restoration of the platen.
  5. In a continuous billing machine, the combination of a carriage, a platen, a pair of movable 75 arms for supporting the platen in the carriage
- whereby the platen may be displaced from a writing position to a non-writing position, means cooperating with the platen when in its writing position to hold work sheets against the platen, means to engage the holding means with the platen and tending to cause the holding means to follow the platen in its movement to non-writing position, an arm pivotally mounted in the carriage and having a connection to operate the holding means, and means carried by one of the arms which support the platen and engaging the second named arm for moving the holding means back toward their normal position while the platen is being restored to writing position.
6. In a continuous billing machine, the combination of a carriage, a platen, and means for movably mounting the platen in the carriage whereby the platen may be displaced from a writing position to a non-writing position including a pair of arms pivotally mounted in the carriage 20 and rotatably supporting the platen, means to latch the platen in its writing position, a lever for releasing said latch means, feed rollers movably mounted in the carriage, means to actuate the feed rollers into engagement with the platen 25 to grip a work sheet between the platen and the feed rollers, said actuating means causing the feed rollers to follow the movement of the platen from its writing to non-writing positions, means having a connection to the feed rollers for restoring the feed rollers, means carried by one of the arms and engageable with the restoring means whereby the restoration of the platen to its writing position causes the restoration of the feed rollers, and means operated by said lever for 30 rendering the means on said arm effective.
7. In a continuous billing machine, the combination of a carriage, a platen movably mounted in the carriage whereby the platen may be displaced from a writing to a non-writing position, means to latch the platen in its writing position, a release lever for the latching means, means to lock the latching means in unlatched position while the platen is being displaced from a writing to a non-writing position, and means carried by 40 the carriage for releasing the latching means when the platen reaches its writing position.
8. In a continuous billing machine, the combination of a carriage, a platen, and means to movably mount the platen in the carriage whereby the platen may be displaced from a writing to a non-writing position including a pair of arms pivotally mounted in the carriage, means carried by said arms and cooperating with part of the carriage for latching the platen in its writing 45 position, a lever for releasing the latching means to permit displacing the platen to non-writing position, and means to lock the latching means in disengaged position, said locking means being 50 disengaged by cooperation with a part of the carriage whereby the latching means is released only when the platen reaches its writing position.
9. In a continuous billing machine, the combination of a carriage, a platen, means to movably 55 support the platen in the carriage whereby the latter may be displaced from a writing to a non-writing position, feed rollers movably mounted in the carriage, means to engage said feed rolls with the platen while it is in its writing position, said 60 means tending to cause the feed rollers to follow the movements of the platen to non-writing position, and means connected to the first named means for operating the feed rollers when the platen is restored to its writing position whereby 65

the feed rollers move in the same direction as the platen during its restoring movement.

10. In a continuous billing machine, the combination of a carriage, and a platen movably mounted in the carriage so as to be displaceable from a writing to a non-writing position, feed rollers cooperating with the platen, means for causing the feed rollers to follow the platen in its movements from a writing to a non-writing position, and means responsive to movement to the platen to its writing position for moving the feed rollers a greater extent toward writing position than said feed rollers move when the platen is displaced to non-writing position whereby the platen is restored to a writing position before the feed rollers reengage the platen.

11. In a continuous billing machine, the combination of a carriage, and a platen movably mounted in the carriage for displacement from a writing to a non-writing position, feed rollers cooperating with the platen, means for causing the feed rollers to follow the movement of the platen from writing to non-writing positions, means responsive to movement of the platen to writing position for restoring the feed rollers to and beyond their normal position and in advance of the platen, and means to cause the feed rollers to reengage the platen when the platen reaches its writing position.

12. In a continuous billing machine, the combination of a carriage and a platen displaceably mounted in the carriage so as to be movable from a writing to a non-writing position, means cooperating with the platen to grip a work sheet when the platen is in its normal position, means to engage the gripping means with the platen, said engaging means tending to cause the gripping means to follow the platen in its movement from a writing to non-writing position, and means responsive to movement of the platen to its non-writing position for preventing reengagement of the gripping means with the platen until the platen reaches its writing position.

13. In a continuous billing machine, the combination of a platen, means to movably mount the platen for movement from a writing position to a non-writing position including a pair of arms, means carried by said arms for latching the platen in its writing position, a lever carried by one of said arms for first releasing said latches and thereafter moving the platen to non-writing position, feed rollers cooperating with the platen when it is in its writing position to feed a work sheet, means to urge the feed rollers into engagement with the platen and tending to cause the feed rollers to follow the movement of the platen a limited extent when the platen is displaced to an unwriting position, feed roller operating arm having a connection to the feed rollers for restoring the feed rollers when the platen is restored to writing position, a member carried by one of the platen supporting arms and engageable with the feed roller operating arm whereby the latter is operated to restore the feed rollers when the platen is restored to its writing position, and means operated by said lever for moving said member into engagement with the feed roller operating arm.

14. In a machine of the class described, a platen, means cooperating with the platen to grip a work sheet, means to movably mount the platen whereby it may be displaced from an operative position to an inoperative position, means to movably mount the gripping means, means cooperating with the second-named mounting means

for resiliently engaging the gripping means with the platen and tending to cause the gripping means to follow the platen in its movement toward inoperative position, and means interconnecting both mounting means for moving the gripping means in the same direction as the platen a predetermined extent when the platen is restored to operative position.

15. In a machine of the class described, a platen, means to mount the platen for movement from an operative to an inoperative position, means cooperating with the platen to grip a work sheet when the platen is in its operative position; means to movably mount the gripping means whereby the latter follows the platen during a portion of the movement of the platen to inoperative position, means operated by the platen mounting means for restoring the gripping means while the platen is being restored to operative position, and means to disable the restoring means when the platen reaches its operative position.

16. In a continuous billing machine the combination with a carriage, feed rollers mounted in the carriage, a platen, means to movably mount the platen in the carriage for displacement to and from a non-writing position, means to urge the feed rollers into engagement with said platen when it is in writing position, said platen when displaced to its non-writing position becoming separated from the feed rollers to provide a space between said rollers and the platen whereby a record sheet gripped between the platen and feed rollers may be straightened, said feed rollers when the platen is displaced to non-writing position following the movement of the platen a limited extent, and means responsive to movement of the platen toward writing position for preventing re-engagement of the feed rollers with the platen until the platen reaches its writing position.

17. In a continuous billing machine the combination of a carriage and a platen movably mounted in the carriage whereby the platen may be displaced from a writing to a non-writing position, said rollers being movably mounted in the carriage and cooperating with the platen when it is in its writing position to feed record sheets, said platen when displaced to non-writing position becoming separated from said feed rollers to permit a record sheet wrapped around the platen to become flattened, means for causing the feed rollers to follow the movement of the platen to the non-writing position a limited extent, and means responsive to movement of the platen to its writing position to prevent re-engagement of the feed rollers with the platen until the platen reaches its typing position.

18. In a typewriting machine the combination of a platen, feed rollers cooperating with the platen to feed a work sheet wrapped around the platen, means to movably mount the platen to permit separation of the platen from the feed rollers to permit a work sheet wrapped around the platen to become flattened, means urging said feed rollers into engagement with the platen whereby the work sheet is resiliently gripped between the platen and the feed rollers, said urging means being operative when the platen is separated from the feed rollers to cause the feed rollers to follow the movement of the platen to a limited extent before actual separation takes place, and means operative upon the restoration of the platen for preventing the en-

gagement of the feed rollers with the platen until the latter reaches its initial position.

19. In a typewriting machine, a platen, means to press a work sheet against the platen whereby rotation of the platen feeds the work sheet; means to move the platen away from the pressing means to provide a space to permit flattening of the work sheet, said pressing means, when the platen is moved, tending to follow the movement of the platen for a portion of its movement; and means to restore the pressing means to its normal position, including an element actuated by movement of the platen toward the pressing means for preventing the re-engagement of the platen with the pressing means until the platen has reached its initial position.

20. In a machine of the class described, a pair of coacting feed rollers for feeding a work sheet, means to movably mount one of said feed rollers for displacement away from the other feed roller to provide a space for manipulating the work sheet, means to movably mount the other feed roller, means to resiliently urge the other feed roller into engagement with the first feed roller to grip the sheet, said second-named feed roller tending to follow the movement of the first feed roller when the latter is displaced, means to limit such movement of the second feed roller whereby the first feed roller becomes separated from the second feed roller when the first feed roller is displaced, means for displacing the feed roller, and means controlled by the displacing means for causing the second feed roller to remain separated from the first feed roller until the latter reaches its initial position.

21. In a machine of the class described, a platen, a paper deflector including a series of feed rollers in engagement with the platen, means to movably mount the platen to permit same to be disengaged from the feed rollers, means to engage the feed rollers with the platen whereby said feed rollers tend to follow the movement of the platen when the latter is disengaged from the feed rollers, means to limit such movement to enable the platen to become separated from the feed rollers, means to dis-

place the platen away from the feed rollers, and means controlled by the displacing means for causing the feed rollers to remain separated from the platen until the platen reaches its initial position.

22. In a machine of the class described, the combination of a pair of coacting feed rollers, manual means for displacing one of said feed rollers away from the other to permit a work sheet therebetween to be manipulated, means to urge the second feed roller into engagement with the other whereby the second-named feed roller tends to follow the movement of the first feed roller when displaced, means to limit such movement to permit said feed rollers to become separated, and means controlled by the displacing means for causing said rollers to remain in separated position when the first-named feed roller is restored to its initial position, said last-named means being effective when the first-named feed roller reaches its initial position to permit the second-named feed roller to re-engage the first-named feed roller.

23. In a continuous billing machine, the combination of a carriage, a platen, a pair of platen displacing arms pivotally mounted in the carriage and operable to displace the platen from a writing to a non-writing position, feed rollers mounted in the carriage and cooperating with the platen to grip a work sheet, means to resiliently urge the feed rollers into engagement with the platen and tending to move the feed rollers in the same direction as the platen when displaced, a control arm pivotally mounted in the carriage and having a connection to the feed rollers, and operating means connected to one of said first named arms and engageable with the control arm to control the engagement of the feed rollers with the platen, said operating means being operative, when the platen is restored to writing position, to impart to the feed rollers, through the control arm therefor, a component of movement away from the platen to maintain the feed rollers out of engagement with the platen until the latter reaches its writing position.

JOHN L. PETZ.
